UNITED STATES PATENT OFFICE.

EMMANUEL DOBROWSKY, OF NEW YORK, N. Y.

CARD HOLDER.

Application filed October 15, 1927. Serial No. 226,373.

This invention relates to card holders and more particularly to card holders for use in connection with advertising apparatus, an object of the invention being to provide improved means whereby cards may be readily secured to the card holder or removed therefrom and replaced by other cards at the will of the operator.

A further object is to provide a device of this character which enables the easy and quick interchange of cards and provides a secure mounting for the cards when in use.

With these and other objects in view, the invention consists in certain novel features of construction and combinations and arrangements of parts, which will be more fully hereinafter described and pointed out in the claims.

In the accompanying drawings—

20 Figure 1 is a view in vertical transverse section through an advertising device embodying my invention;

Figure 2 is an end view of my improved card supporting drum;

25 Figure 3 is a view in front elevation of my improved card supporting drum with cards in position thereon;

Figure 4 is a plan view showing one of my improved card holders with the cards in position therein;

30 Figure 5 is a fragmentary broken view in plan showing my improved card holder in operative position;

Figure 6 is a view similar to Figure 5, 35 taken in longitudinal section on the line 6—6 of Figure 5;

Figure 7 is a view in section on the line 7—7 of Figure 5.

1 represents a casing in which a drum 2 has 40 rotary mounting. This drum 2 is provided with disks 3 at its ends, carrying a circular series of card holders 4 pivotally mounted in the disks and supporting cards 5. As the drum is turned to move the cards past a holding device 6 the cards fall in vertical position so that an upper and a lower card are exposed at the same time, as clearly indicated in Figure 1 and 3.

Each card holder 4 comprises two longitudinal sections 7 and 8. As a matter of fact, the section 7 provides a recess for the accommodation of section 8, the latter being removable, and both sections of semicircular form in cross section.

55 The removable section 8 has a beveled end 9 adapted to fit under a beveled tongue 10 ad-

jacent one end of the section 7, and said section 8 carries a pivoted turn button 11 which is adapted to engage in a recess 12 in the opposite portion of section 7. This turn button 60 11 is fixed to a screw 13 which has rotary mounting in section 9 so that it may be readily turned by the use of an ordinary screw driver.

A series of headed studs 14 are secured to 65 the section 7, and section 8 is made with key-hole slots 15 to receive said studs 14. Furthermore, the face portions of the section 8 in which the keyhole slots 15 are provided are flattened and slightly beveled, as indicated at 70 16, so that when the headed studs are projected through the larger ends of the slots 15 and the section 8 moved longitudinally there will be a certain cam action to force the sections together.

75 17 represent cards which may be of card-board or any other suitable material, and which are perforated, as shown at 18, to receive the studs 14.

To remove the section 8 and the cards 17 it 80 is necessary to first turn the turn button 11 through the medium of the screw 13 to the position shown in dotted lines in Figure 5. The section 8 can then be moved to the right of Figure 5, moving the larger ends of the key-hole slots 15 into register with the headed studs 14 and drawing the beveled end 9 of 85 said section 8 from under the beveled tongue 10 of section 7. The section 8 can then be removed and the cards can be removed and new 90 cards can be placed on the studs and the section 8 returned to position on the studs with the studs in the larger ends of the slots, and then when said section 8 is moved longitudinally or to the right of Figures 5 and 6, the 95 turn button 11 can be operated to move the same into position longitudinally of the sections and securely hold the sections in clamping position relative to the cards.

The disk 3 at one end of the drum 2 is provided with bearing recesses 19 to receive trunnions 20 on one end of rod sections 7, said rod sections 7 at their other ends having trunnions 21 which are longer than the trunnions 20 and which are adapted to be projected 100 through openings 22 in the other of said disks 3. This last mentioned disk 3 carries on its outer face a spring metal disk 23 having radial slits 24 therein whereby a series of radial spring tongues 25 are provided which 105 engage the ends of trunnions 21.

This construction facilitates the assem-

blage of the card holders in the drums, the operation being as follows:

The long trunnion 21 is first inserted through the opening 22 to force the spring 5 tongue 25 outwardly far enough to allow the trunnion 20 to be positioned in the bearing recess 19, when the parts can be moved to the left of Figure 6 and held in this position by the spring tongue 25.

10 This means of coupling the card holders to the drum facilitates the quick assemblage of the parts and the quick removal of the card holders but does not in any way interfere with the pivotal mounting of the card holders 15 to allow the cards to move in the operation of the advertising device.

Various changes and alterations might be made in the general form of the parts described without departing from my invention and hence I do not limit myself to the precise details set forth but consider myself at liberty to make such changes and alterations as fairly fall within the spirit and scope 20 of the appended claims.

25 I claim:

1. A card holder, comprising two sections, one section recessed receiving the other section, said sections having stud and slot connection, and a turn button on one section engaging the other section and holding the parts against independent longitudinal movement.

2. A card holder, including a recessed section and a removable section fitting in the recessed section, said recessed section having a beveled tongue adjacent one end and said removable section having a beveled end fitting under said tongue, and a turn button on the removable section adapted to engage in a recess in the recessed section and holding the sections against independent longitudinal movement, headed studs carried by one section, and keyhole slots in the other section receiving the studs.

3. A card holder, including a recessed section and a removable section fitting in the recessed section, said recessed section having a beveled tongue adjacent one end and said removable section having a beveled end fitting under said tongue, a turn button on the removable section adapted to engage in a recess in the recessed section and hold the sections against independent longitudinal movement, headed studs carried by one section, keyhole slots in the other section receiving the studs, and perforated cards adapted to be positioned between the sections and receive the studs through the perforations of the cards.

Signed at New York, in the county of New York and State of New York this 11th day of July A. D. 1927.

EMMANUEL DOBROWSKY.
